UNITED STATES PATENT OFFICE.

HALVER R. STRAIGHT, OF ADEL, IOWA, ASSIGNOR TO ETHEL H. STRAIGHT, OF ADEL, IOWA.

DRIER FOR CERAMIC WARES.

Application filed January 3, 1927. Serial No. 158,689.

This invention relates to driers for ceramic ware.

The object of my invention is to provide a drier of simple, durable and inexpensive construction, provided with means whereby ware may be advanced through the drier in a progressive manner from one end to the other, and at a comparatively uniform speed; and also to provide means for advancing the drying medium through said drier from one end to the other under a slight pressure, and in the opposite direction from the movement of the ware through said drier; and to provide in connection therewith means for circulating the medium through the ware vertically in such a manner that the drier may be divided into somewhat separate circulating zones, one of the zones being provided with means for circulating the medium through the ware in a given zone a greater number of times than in an adjoining zone, and to provide means whereby the number of cycles of circulation in each zone may be varied at the will of the operator, so that the velocity of the drying medium may be varied inversely to the shrinkage rate of the ware being dried, it being generally the rule that ceramic wares shrink more in proportion to the loss of moisture in the early part of the drying than later when drying has partly taken place.

A further object is to so construct and arrange the mechanism for accomplishing the above results that the speed of the movement of the medium between two adjacent zones is maintained at a comparatively low rate, so that sudden changes in the speed of the drying between two zones will be eliminated.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a transverse sectional view through my improved drier.

Figure 2 is a longitudinal sectional view. 50 Figure 3 is a sectional view taken on the line 3—3 of Figure 1.

Figure 4 is a detail sectional view taken on the line 4—4 of Figure 1.

My improved drier comprises upright wall 55 members 10 and end members 11 and 12, and

a top 13, preferably arranged in the form of an arch. Spaced inwardly from each of the wall members 10 is a partition 14, the lower edge of which is supported a slight distance above the floor line of the drier. A number 60 of transversely arranged partitions 15 are provided to form a series of vertically arranged compartments or passages adjacent to the inner face of each of the wall members 10. The upper edges of the partitions 14 and 15 are provided with an inclined top 16 provided with a series of depressions 17 having horizontally arranged portions 18. Each of said members 18 is provided with a circular opening 19. In each of the openings 19 is a fan 20 supported on the lower end of a vertically arranged shaft 21 rotatively mounted in a vertical sleeve 22 supported in the top member 13. The upper end of the shaft 21 is provided with an electric 70 motor 23, each of said motors being independently operated by suitable mechanism not illustrated, so that the said motors may be operated at various speeds if so desired.

Supported longitudinally in the bottom 80 of the drier is a track 24 designed to support ware bearing cars 25. The side edges of each of the said cars are provided with a downwardly extending flange 26 designed to enter the usual sand seal 27. The upper 85 face of the car 25 is provided with a series of transversely arranged passages 28 open at their tops and designed to communicate with vertical passages 29 in the ware 30 stacked on said car. The lower edge of the 90 partitions 14 terminate at a point substantially in line with the upper edges of the passages 28, so that the drying medium may be moved vertically through the passages 29 and horizontally through the passages 28 to 95 the compartments 31 formed between the partitions 14 and 15, and thence upwardly through the openings 19. A sand seal 32 is provided between the lower ends of the partitions 14 and the side edges of the stack of 100 ware, so that all of the air being circulated will have to travel through the passages 29.

The compartments 31 are provided with heating coils 33 which extend horizontally and longitudinally through the drier. Each 105 end of each set of coils is provided with a header 34, one of which is provided with an outlet pipe 35 for receiving heated gases, and the other header is provided with an intake pipe 36.

A fan 39 is supported in the upper end of the end member 12, and provides means for forcing the drying medium into the drier. An outlet pipe 40 is provided at the opposite 5 end through which the moisture-laden medium will be discharged.

It will be seen, by referring to Figure 3, that I have provided at each side of the drier a number of compartments 31, some of 10 the compartments at the left hand end of the kiln, as shown in said figure, being of a length considerably greater than those at the right hand end. It will further be seen that each of the compartments 31 is provided with the fan 20 in its upper end for 15 circulating the drying medium through said compartments. By providing the compartments of various lengths, it will be seen that the medium in one compartment may be circulated at a higher velocity than the medium in another compartment, with the speed of 20 both of the fans is substantially the same.

I have found by experience that the length of each of the compartments 31 may be determined, so that the velocity of the 25 medium in the various zones may be approximately maintained when the fans are operating at substantially the same speeds. In practice, however, it is necessary to vary the 30 speed of the fans somewhat in order to meet the working conditions of the ware as it is being passed through the drier. In operation, the ware is advanced through the drier from the left hand end to the right, as 35 shown in Figure 3, while the drying medium is introduced through the fan 39 at the opposite end of the drier. The fans 20 in the left hand end will then cause the medium to be drawn downwardly through the passages 40 29 and upwardly through the said openings 19. The transverse velocity of the medium is greater than the advance of the same 45 through the drier, so that the medium is circulated a number of times through the first set of compartments in a recirculating path and then advanced to the second set of compartments, at which time the transverse movement of the medium is considerably decreased, due to the fact that the second compartment is longer than the first. This cycle 50 of operation continues throughout the length of the drier, the medium passing between the heating coils 33 in each of its cycles, which causes the said medium to be reheated each 55 time.

It is desirable to provide a comparatively low velocity of the medium at the time the ware enters the drier, inasmuch as the shrinkage of the ware is comparatively high 60 as the first part of the moisture is removed. After a large part of the shrinkage has taken place, the velocity of the medium may be increased without warping or cracking the ware. The heated gases are caused to 65 enter through the pipe 36, and for that rea-

son the pipes passing through the shorter compartments are of higher temperature than those passing through the longer compartments, and the medium at the delivery end of the drier will be maintained at a high 70 temperature, and at the same time operate at a higher velocity.

To further assist in causing the drying medium to circulate vertically through the ware, I have supported between the adjoining 75 ends of two adjacent cars a strip of paper 38, or similar material, of cheap construction, and of such size as to fit the opening through which the car enters the drier, said paper having its side edges engaging 80 the wall members 14. These papers prevent any longitudinal movement of the medium through the ware from one end to the other.

Thus it will be seen that I have provided a drier of comparatively simple construction, in which the circulation of the medium may be very accurately controlled throughout the various drying zones, and provided with means whereby the velocity of the medium may be increased or decreased in a given zone, and the rate of the drying of the ware in that particular zone controlled proportionately, so that the ware may be advanced through the drier in a minimum length of time without warping or crack- 95 ing the ware.

I claim as my invention:

1. A drier comprising side walls, end walls and a top to form a drier chamber, partitions arranged adjacent to the inner 100 face of said side walls to form vertically arranged compartments, each of said compartments being provided with an inlet opening at its lower end and an outlet opening at its upper end, heating coils extending longitudinally through each set of compartments, means for conveying ware through said drier between the said compartments, said conveying means being provided with transversely arranged passages 105 designed to communicate with vertically arranged passages in the ware stacked thereon, a fan in each of the openings in the upper end of said compartments, said fans being independently operated, means for introducing a drying medium in one end of said drying chamber, and said chamber being provided with an outlet opening in its opposite end.

2. A drier comprising side walls, end walls, and a top to form a drier chamber, partitions arranged parallel with the inner 120 faces of said side walls to form vertically arranged compartments, each of said compartments being provided with an inlet opening at its lower end and an outlet opening at its upper end, heating coils extending longitudinally through each set of compartments, means for conveying ware 125 through said drier between said compartments,

ments, said means comprising a series of continuously moving and adjacent cars, each of said cars having its upper surface provided with horizontally arranged passages 5 designed to communicate with vertically arranged passages formed in ware stacked thereon to be dried, the ends of the horizontally arranged passages communicating with the inlet openings of said compartments, 10 sealing means supported above and below the outlet openings of said compartments and the ends of said horizontal passages, a fan in each of the openings in the upper ends of said compartments, said fans being independently operated, and means for introducing a drying medium in one end of 15 said drying chamber under slight pressure, said chamber having an outlet opening at its opposite end for said drying medium.

20 3. A drier comprising side walls, end walls, and a top to form a drier chamber, partitions arranged parallel with the inner faces of said side walls to form vertically arranged compartments, each of said compartments being provided with an inlet opening at its lower end and an outlet opening at its upper end, heating coils extending longitudinally through each set of compartments,

means for conveying ware through said drier between said compartments, said means comprising a series of continuously moving and adjacent cars, each of said cars having its upper surface provided with horizontally arranged passages 30 designed to communicate with vertically arranged passages formed in ware stacked thereon to be dried, the ends of the horizontally arranged passages communicating with the inlet openings of said compartments, sealing means supported above and below the outlet openings of said compartments and the ends of said horizontal passages, a fan in each of the openings in the upper ends of said compartments, said fans being independently operated, means for introducing 35 a drying medium in one end of said drying chamber under slight pressure, said chamber having an outlet opening at its opposite end for said drying medium, and a sheet of light and inexpensive material fixed to and supported between the adjoining ends of two adjacent cars and the ware stacked thereon for sealing the ends of the stacks of ware against longitudinal movement of the drying medium through the ware.

HALVER R. STRAIGHT.
